COLLAPSIBLE YARN REEL

Fred Schoditsch, Elyria, Ohio

Application August 30, 1946, Serial No. 693,903

4 Claims. (Cl. 242—114)

1

The present invention relates to new and useful improvements in yarn reels for use when unraveling yarn from a skein and the invention has for its primary object to provide a reel on which the yarn may be wound to maintain the same against tangling while subsequently winding the yarn into a ball.

A further object of the invention is to provide a yarn winding reel of this character constructed from collapsible parts whereby the reel may be dismantled and stored in a compact form when not in use.

A further object of the invention is to provide a device of this character of simple and practical construction, which may be manufactured from inexpensive material and which at the same time is efficient and reliable in use and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view;

Figure 2 is a top plan view;

Figure 3 is an end elevational view;

Figure 4 is a sectional view taken on a line 4—4 of Figure 2, and

Figure 5 is a vertical sectional view taken on a line 5—5 of Figure 1.

Referring now to the drawings in detail wherein for the purpose of illustration I have disclosed a preferred embodiment of the invention, the numeral 5 designates a base generally and which includes an elongated strip of wood or other light weight inexpensive material 6 on the outer end of which is positioned a cross strip 7 and secured in cross relation on the strip 6 by means of a dowel 8. To the underside of the cross strip 7, at the outer end thereof, are cemented blocks 9 to support the ends of the cross strips against tilting movement.

An elongated block 10 is positioned on the strip 6 of the base 5, the block 10 and strip 6 being coextensive in width, one end of the block having an upright 11 of flat material secured thereto by a dowel 12, the outer side of the post bearing against the cross strip 7. The post is formed with a tapered yarn feeding opening 11a.

The other end of the block 10 is formed with a vertical bore 13 in which a dowel pin 14 is positioned projecting above the upper flat substantially horizontal edge 13a of the block and

2

on which a reel designated generally at 15 is journaled for horizontal rotary movement. A washer 16 is positioned between the reel and the upper surface of the block 10.

The reel 15 is constructed of spokes 17 and 18 formed of flat strips of material arranged in cross relation and journaled on the upper end of the dowel pin 14. A dowel 19 connects the spokes 17 and 18 to each other for rotation as a unit.

Angle members 20 are suitably secured on the upper surface of the spoke 17 at the ends thereof to form outwardly opening channels at the ends of the spoke and similar yokes or channel members 21 are secured or integrally formed with plates 22 slidably mounted on the upper surface of the spokes 18 adjacent the outer ends thereof. The plates 22 are provided with longitudinally extending slots 23 in which the guide pins 24 and bolts and wing nuts 25 are slidably received, the guide pins and bolts extending upwardly from the spoke 18 through the slots to secure the yokes or channel members 21 in radially adjusted position on the spokes.

In the operation of the device as the yarn is unraveled the same is fed through the opening 11a in post 11 to hold the yarn horizontally while it is wound on the yokes or channel members 20 and 21 of the spokes as the latter are rotated. The radial adjustment of the yokes 21 varies the diameter of the reel.

I claim:

1. A reel comprising a base, a vertical shaft rising therefrom, a plurality of double-ended spokes journaled on the shaft, means detachably connecting the spokes to each other in crossed relation for rotation as a unit, a yoke at each end of the spokes for winding strands of material thereon, said yokes including base strips engaging the spokes and provided with longitudinal slots, guide pins fixed to the spokes slidably engaging the slots in said base strips, and adjustable fasteners carried by the spokes for holding the base strips against sliding movement, said fasteners being spaced parallel to said guide pins and received in said slots to coact with the guide pins in preventing lateral movement of said yokes relative to said spokes.

2. A reel comprising a base, an elongated block carried by the base having an upper edge spaced parallel to the longitudinal axis of the base, said block having a vertical bore extending through the upper edge at right angles thereto, a shaft fixed to the base and extending outwardly through the vertical bore in said block, a bearing washer embracing the shaft and engaging the

upper edge of the block, a plurality of double-ended spokes journalled on the shaft and bearing upon the washer, means detachably connecting the spokes to each other in crossed relation for rotation as a unit, a yoke at each end of the spokes including base strips having longitudinal guide slots, guide pins carried by said spokes for slidably engaging the slots provided in the base strips, and adjustable fasteners carried by the spokes for holding the yokes against sliding movement.

3. The combination of claim 2 wherein said means detachably connecting the spokes to each other includes a dowel pin connecting the centers of the spokes to each other.

4. A reel comprising a base, an elongated block carried by the base having an upper edge spaced parallel to the longitudinal axis of the base, said block having a vertical bore extending through the upper edge at right angles thereto, a shaft fixed to the base and extending outwardly through the vertical bore in said block, a bearing washer embracing the shaft and engaging the upper edge of the block, a plurality of double-ended spokes journalled on the shaft and bearing

10

25

upon the washer, means detachably connecting the spokes to each other in crossed relation for rotation as a unit, a yoke at each end of the spokes including base strips having longitudinal guide slots, guide pins carried by said spokes for slidably engaging the slots provided in the base strips, adjustable fasteners carried by the spokes for holding the yokes against sliding movement, an upright having a feed opening therein for feeding a strand of material horizontally to the yokes, and means for removably securing the upright to the block.

FRED SCHODITSCH.
